UNITED STATES PATENT OFFICE.

GEORGE P. HOGAN, OF CHICAGO, ILLINOIS.

WEAR PLATE FOR RUBBER HEELS.

Application filed July 17, 1924. Serial No. 726,431.

To all whom it may concern:

Be it known that I, GEORGE P. HOGAN, a citizen of the United States, residing at Chicago, in the county of Cook and State 5 of Illinois, have invented a certain new and useful Wear Plate for Rubber Heels, of which the following is a specification.

This invention relates generally to wear plates for boots and shoes and more particularly to wear plates for rubber heels.

One object of my invention is to provide a wear plate with an improved means for attachment to rubber heels including a means for locking the plate in position on 15 the heel to prevent loosening of the plate in service.

Another object is to provide a wear plate of novel construction which is of substantially uniform thickness and which is adapted to be set in a rubber heel to afford a wearing surface above the tread of the heel without exposing sharp corners or edges.

A further object is to provide an improved wear plate for rubber heels which 25 may be securely attached to the heel before the latter is secured to the shoe and which may be easily detached and replaced while the heel is fastened to the shoe.

Other and ancillary objects and advantages will become apparent as the description proceeds.

In the drawings, Figure 1 is a plan view of the wear plate attached to a rubber heel.

Fig. 2 is an enlarged vertical section on the line 2—2 of Fig. 1.

Fig. 3 is a vertical section on the line 3—3 of Fig. 1.

Fig. 4 is a fragmentary view along the line 4—4 of Fig. 2.

Referring to the drawings which illustrate the preferred embodiment of my invention the numeral 10 represents a wear plate fastened to a rubber heel 11 by means of a bolt 12, a nut 13, and a locking plate 14.

The wear plate 10 is usually cut from flat stock of uniform thickness in the form of an ellipse although it may be of any other suitable shape. An opening 15 is countersunk near the center of the wear plate of proper depth to allow the flat head of a bolt to be held therein substantially below its outer edges. In the countersinking operation a tapering projection or boss 16 is formed on the opposite or inner side 55 of the plate thereby maintaining the uniform thickness thereof. All of the edges of

the plate are bent downward from the center to form the convex outer wearing surface 17 and the concave inner surface 18.

To receive the inner face of the wear plate 10 the rubber heel 11 is provided with a recess 19. This recess may be positioned in any portion of the heel to suit the individual wearer and is preferably formed when the heel is molded. To be of proper depth the recess 19 should allow the edges of the wear plate to rest therein slightly below the wearing face 20 of the heel. Thus when the wear plate is in such adjusted position its convex wearing surface 17 extends substantially above the wearing face of the heel without leaving protruding edges to catch on the steps of stairways and the like and trip the wearer. The forward edge 21 of the plate 10 may if desired be bent 75 downward more than the other edges.

The bolt 12, whose head 22 is held in the countersunk opening 15, extends through the hole 23 and threads into a nut 13 in a recess 24 on the inner side of the heel. The edges of the recess 24, corresponding substantially to the dimensions of the nut, will prevent rotational movement of the latter while the bolt 12 is being tightened. Thus when the wear plate 10 and nut 13 are held 80 in their respective recesses and the bolt 12 is properly tightened, the rubber heel will be securely clamped between the nut and the wear plate. The wear plate, therefore, 85 forms a unitary part of the heel, and if desired it may be attached to the heel by the heel manufacturer.

Preferably I provide means for locking the bolt 12 against rotational movement. For this purpose the end of the bolt 12 95 may be flattened and adapted to coact with a slot in the shoe when the heel is placed thereon. To this end I have shown herein a slot 26 in a metal locking plate 14. The plate 14 may be set in the leather lift 28 100 and suitably secured thereto by nails 27.

In applying the wear plate to the heel of a shoe, the locking plate 14 is first set in the leather lift 28 so that the rectangular slot 26 will be alined with the hole 23 in the rubber heel. The rubber heel with wear plate securely clamped thereto is then fastened to the shoe by suitable means such as nails 29 with their heads resting against metallic washers 30 in the usual way. In 110 this position the flattened end 25 of the bolt extends through the locking plate 14 and

engages the sides of the rectangular slot 26 thereof to lock the bolt against rotational movement.

To remove the bolt it is merely necessary 5 to insert a flat tool such as a screw driver between the rubber heel 11 and the leather lift 28 and raise the former until the end of the bolt is out of engagement with the slot. Then the bolt may be unscrewed, and 10 the worn out wear plate may be replaced. The screw driver also serves to hold the nut 13 in the recess 24 while the bolt is removed.

It will be apparent that I have provided 15 a means for materially increasing the life of rubber heels. The concavo-convex curvature of wear plate permits its major portion to project above the surface of the heel, and by setting the plate in a recess 20 formed in the heel, it is possible to avoid reducing the thickness of the edges, at the same time eliminating any protruding edges which might catch on sharp objects or projections. Such wear plates may be securely 25 attached to all kinds of rubber heels in any desired position thereon before the heels are fastened to the shoes. After the rubber heel has been placed on the shoe, the wear plate cannot become loosened. On the 30 other hand worn out plates may be readily replaced without the services of shoe repairer and without removing the heel from the shoe.

While I have shown in the drawings and 35 have described herein in detail the preferred embodiment of my invention for the purpose of illustration, it is to be understood that I do not thereby intend to limit my invention to the construction shown, but aim

in the following claims to cover all modifications and alternative constructions falling within the spirit and scope of the invention.

I claim as my invention:

1. The combination with a leather heel 40 lift and a rubber heel secured to said lift, of a wear plate on the tread of said rubber heel, a nut on the under side of said heel, a bolt clamping said heel between said nut and said wear plate and having a flattened end projecting beyond said nut, and a locking plate secured to said lift opposite said nut and having a slot therein receiving the flattened end of said bolt and thereby locking it against rotational movement, said heel, when attached to said lift, being adapted to be separated from the lift 45 sufficiently to unlock the bolt and permit removal of said wear plate.

2. The combination with a leather heel 50 lift and a rubber heel secured thereto, of a wear plate and a nut positioned respectively on the outer and inner sides of said heel, a bolt clamping said heel between said wear plate and said nut, said bolt having a flattened end projecting beyond said nut into 55 to said lift, and means providing a recess in said leather lift receiving said flattened end, said recess having sides cooperating with said flattened end to prevent rotation 60 of said bolt, said bolt being removable from said heel when the heel and lift are separated sufficiently to withdraw said flattened end from said recess.

In testimony whereof I have hereunto 65 affixed my signature.

GEORGE P. HOGAN.
